UNITED STATES PATENT OFFICE.

EUGENE L. WATSON, OF DEMING, WASHINGTON.

CATTLE-GUARD.

1,206,390.

Specification of Letters Patent. Patented Nov. 28, 1916.

Application filed February 4, 1916. Serial No. 76,193.

To all whom it may concern:

Be it known that I, EUGENE L. WATSON, a citizen of the United States, residing at Deming, in the county of Whatcom and State of Washington, have invented certain new and useful Improvements in Cattle-Guards; and I do hereby declare the following to be a full, clear, and exact description of the invention, such as will enable others skilled in the art to which it appertains to make and use the same.

The primary object of this invention is to improve the construction of cattle guards for railroads by providing a cheap, durable and efficient guard that will positively prevent cattle from crossing the track, and which can be conveniently and expeditiously placed in position on the track.

Other objects will appear and be better understood from that embodiment of my invention of which the following is a specification, reference being had to the accompanying drawings forming a part thereof, in which:

Figure 1 is a top plan view of the cattle guard showing the same applied to the track. Fig. 2 is a transverse sectional view taken on line 2—2 of Fig. 1, and Fig. 3 is a detail sectional view taken on the line 3—3 of Fig. 1. Fig. 4 is a horizontal section taken through Fig. 1, Fig. 5 is a perspective view of one of the anchor plates, Fig. 6 is a horizontal sectional detail, showing the manner of connecting one end of the roller 35 to the adjacent plate and anchor.

Referring to the drawings, the numeral 1 designates the rail ties of ordinary construction, adapted to support the rails 2.

Positioned on the upper sides of adjacent ties are L-shaped plates 3. These L-shaped plates are located on the opposite end of the tie, and also positioned on those portions of the ties that are located between the rails 2. The L-shaped plates 3 carried by one tie are arranged directly opposite the plates on the other tie, and the said plates, each have one of their sides secured to the adjacent tie, by bolts 4 and has its other side extending upwardly, as at 5. Located at a point midway between the ties, and at opposite sides of the rails, are rectangular shaped central plates 6. These central plates extend at right angles to the rails 2, and parallel with the sides 5 of the L-shaped plate 3, and have their ends secured in any suitable manner to the web and base flanges of the rails 2.

Rotatably positioned on opposite sides of the central plates 6 and on opposite sides of the rails 2, are a plurality of elongated rollers 7. Each of these rollers is formed preferably of galvanized iron, pressed into substantially star-shape in cross section so as to provide the longitudinal ribs, each of which is, as shown in Fig. 2, of substantially V-shape in cross section, and each roller has a central passage designated 8, extending therethrough, the said passages 8 in the rollers, alining with spaced openings in the sides 5 of the L-shaped plate, and openings 9 in the central plate 6. The rods 10 extend loosely through the passages 8 in the rollers 7 and through the openings 9 in the central plate 6, and have their opposite ends secured in the openings in the opposed sides 5 of the L-shaped plate 3. Each L-shaped plate 3 has associated therewith an anchor plate, designated by the numeral 11, as an entirety. As shown in Fig. 5, each anchor plate is of substantially acute angular shape in cross section, including the side portions 12 and 13. The side 12 is considerably shorter in length than the side 13 and engages against the outer side of the vertical arm 5 of the L-shaped plate 3, and is provided at spaced points with U-shaped slots 14. The opposite ends of the rods 10, are reduced, as shown at 15, and the terminals of the rods are flanged to provide circular heads 16. The diameters of the openings 9, in the vertical arms 5 upon the L-shaped plates, are greater than the diameters of the heads 16, so as to admit of the passage of the heads through the openings 9, and beyond the outer sides of the arms 5, as shown in Figs. 3 and 6 of the drawings. When the anchor plates are in position, the U-shaped slots 14 in the sides 12 thereof, receive the reduced portions 15 on the adjacent ends of shafts 10 as shown in Fig. 3, and the circular heads 16 engage the inner surfaces of the sides 12. The longer sides 13 of the anchor plates, are disposed at such angles and are of such length, that they extend a considerable distance beyond the adjacent edges of the adjacent tie, as shown in Fig. 3, and the short arms of the angular plates 12 are secured to the adjacent sides of the L-shaped plates by means of bolts adapted to extend through openings 17 formed in the sides 12 and through similar openings in the adjacent side of the L-shaped plates.

In use, when the cattle step upon the roll-

ers, the same will rotate and thereby prevent the cattle from obtaining a foot-hold so as to prevent passage over the rails.

Having thus described my invention what I claim as new is:—

In a cattle guard for railroads, the combination with a plurality of plates mounted on adjacent rail ties, and on opposite sides of the rails and provided with a plurality of 10 openings, a plurality of shafts positioned between adjacent ties and having their opposite ends arranged within the openings in the adjacent plates, heads carried by the ends of the shafts and lying in spaced relation with the adjacent plates, rollers journaled on the shafts, anchor plates associated 15 with the first-mentioned plates on the ties

and each including an angular body having one side thereof arranged in engagement with the adjacent plate on the adjacent tie 20 and having a plurality of slots therein for receiving the reduced portions of the shafts, at points between the heads and the first-mentioned plates, the said anchor plate having its opposite side spaced from the adjacent tie and extending outwardly and beyond the same, as and for the purpose specified.

In testimony whereof I affix my signature in presence of two witnesses.

EUGENE L. WATSON.
